UNITED STATES PATENT OFFICE.

ANNIE E. PARSONS, OF BOSTON, MASSACHUSETTS.

CORSET.

SPECIFICATION forming part of Letters Patent No. 700,556, dated May 20, 1902.

Application filed January 2, 1902. Serial No. 88,014. (No model.)

To all whom it may concern:

Be it known that I, ANNIE E. PARSONS, of Boston, in the county of Suffolk and State of Massachusetts, have invented certain new and 5 useful Improvements in Corsets, of which the following is a specification.

This invention has for its object to provide a corset which while affording all the support desirable for the portions of the body which 10 it covers shall be flexible at its waist portion, so that the wearer's body can bend or move freely in various directions, and particularly sidewise, without discomfort and without injury to the corset.

15 The invention consists in the improvement which I will now proceed to describe and claim.

Of the accompanying drawings, forming a part of this specification, Figure 1 represents 20 a side view of one of the side sections or halves of my improved corset. Fig. 1^a represents a section on the line 1^a 1^a, Fig. 1. Fig. 2 represents a perspective view of the complete corset. Fig. 3 represents a front 25 view or elevation of the same.

The same letters of reference indicate the same parts in all the figures.

My improved corset is composed of two side pieces or sections, which are of the general 30 construction shown in Fig. 1 and each having at its front edge a vertical stiffening member or clasp *a*, extending continuously from the upper to the lower end of the corset, one of said clasps being provided with socket 35 coupling members *a'* and the other with stud members *a''*, adapted to engage the socket members, as usual. The rear edge of each of the side sections or corset-halves is provided 40 with one or more vertical continuous stiffening members *b*, two of said members being shown in this case, there being a row of eyelets *c* between the members *b* for the reception of the usual back lacing *d*.

45 *e e* represent a series of horizontal stiffening members, preferably strips of whalebone, located close together, edge to edge, and extending across the waist portion of the corset from the front vertical stiffening members *a* to the rear vertical stiffening members *b*. 50 Said members *e* are arranged in close proximity to each other and practically edge to edge, there being only a sufficient separation

between each member *e* and the next to permit the flexible cloth covering-strips *f*, which are placed upon opposite sides of said members *e*, to be connected between the members by lines *g* of stitches. The covering-strips *f* form parts of the body of the corset and are suitably-stitched thereto, the said covering-strips *f* and the stitches *g*, uniting them between the stiffening members *e*, constituting flexible connections between the said stiffening members *e*. The members *e* and the flexible connections between them constitute elongated hinges extending horizontally along the 65 waist portion of the corset from front to rear. Said hinge portions are practically inextensible lengthwise, so that they prevent the expansion of the waist portion, and are flexible crosswise, so that they permit the free bending 70 of the body above the waist portion in various directions, and particularly sidewise.

75 *g g* represent a series of shorter vertical stiffening members, preferably strips of whalebone, extending from the upper edges of the hinge portions to the upper end of the corset, and *g' g'* represent similar shorter stiffening members extending from the lower edges of the hinge portions to the lower end of the corset. Said shorter stiffening members *g g'* afford the desired support to the portions of the 80 body covered by the corset immediately above and below the said hinges without interfering in any way with the above-described action of the hinges. The inner ends of the members *g g'* are inserted in sockets *h h'*, which are affixed to the body of the corset, the sockets *h* being above the members *e* and opening upwardly to oppose downward movement of the members *g*, while the sockets *h'* are located 85 below the members *e* and open downwardly to oppose upward movement of the members *g'*. Said sockets prevent the vertical members *g g'* from encroaching upon the hinge portions of the corset. 90

95 It will be seen from the foregoing that my improved corset affords all necessary and desirable support to the body, besides permitting freedom of movement to the body, which would not be possible if the shorter vertical 100 stiffening members extended continuously from the upper to the lower end of the corset.

I am aware that it has been heretofore proposed to employ two series of shorter vertical

stiffening members, one series extending from the upper end of the corset downwardly to the neighborhood of the waist portion and the other series extending upwardly from the 5 lower end of the corset to the neighborhood of the waist portion, leaving a flexible portion between the two series. I am not aware, however, that prior to my invention this flexible portion has been occupied by a series of 10 horizontal stiffening-strips flexibly connected and constituting elongated hinges and two series of sockets, one series opposing downward movement of the upper stiffening members, while the other series opposes upward movement of the lower stiffening members.

My improved corset is particularly adapted for the development of the bust and has been found to operate advantageously in this respect.

20 I claim—

A corset composed of two side sections or halves, each having continuous stiffening members at its front and rear edges extending from the upper to the lower end of the 25 corset, a plurality of horizontal stiffening members arranged edge to edge and extend-

ing between said vertical members at the waist portion of the corset, flexible connections between the horizontal members, said horizontal members and connections constituting elongated hinges at the waist portion of the corset, two series of shorter vertical stiffening members extending from said hinges, one to the upper and the other to the lower end of the corset, and two series of metallic 30 sockets attached to the body of the corset at opposite edges of said hinges, the series above the hinges being closed at their lower ends, while the series below the hinges are closed at their upper ends, one series of sockets opposing downward movement of the shorter vertical stiffening members above the hinges, while the other series of sockets oppose upward movement of the shorter vertical stiffening members below the hinges.

40 In testimony whereof I have affixed my signature in presence of two witnesses.

45 ANNIE E. PARSONS.
